UNITED STATES PATENT OFFICE.

OLE RUDD, OF WEST DULUTH, MINNESOTA.

POWER-SHAFT COUPLING.

SPECIFICATION forming part of Letters Patent No. 707,357, dated August 19, 1902.

Application filed March 17, 1902. Serial No. 98,613. (No model.)

To all whom it may concern:

Be it known that I, OLE RUDD, a citizen of the United States, residing at West Duluth, in the county of St. Louis and State of Minnesota, have invented certain new and useful Improvements in Power-Shaft Couplings; and I do hereby declare the following to be a full, clear, and exact description of the invention, such as will enable others skilled in the art to which it appertains to make and use the same.

My invention relates to couplings for power-shafts, and has for its object the provision of a coupling with which two sections of a shaft may be readily and quickly coupled without projecting bolt heads or nuts.

It consists of coöperating collars secured, respectively, upon the opposing ends of adjoining sections of the shaft and formed with engaging faces by which one collar is adapted to mesh with the opposite collar and of key-wedges or locking-pins to lock said collars in engagement.

It also consists of certain other constructions, combinations, and arrangements of parts, as will be hereinafter more particularly set forth and claimed.

In the accompanying drawings, Figure 1 is an end elevation of one section of the shaft, showing one of the coupling-collars applied thereto. Fig. 2 is a similar view of the end of the opposing shaft-section with its coupling-collar in position. Fig. 3 is a side elevation of a portion of the sections of the shaft with their coupling-collars in position and separate. Fig. 4 is a similar view, but showing the coupling-collars applied together. Fig. 5 is a sectional view through the coupling-collars applied together, the shaft-sections being shown in elevation; and Fig. 6 is an enlarged perspective view of one of the key-wedges employed in locking the coupling-collars together.

It has been found desirable in the construction of power-shaft couplings to obviate the use of all fastening means which project from the coupling and which are liable to engage the clothing of attendants and also to minimize the number of parts involved without impairing the strength of the construction. To effect this purpose, I construct the collar

A, adapted to receive the end of a section E of a power-shaft, which collar is enlarged at the forward end and provided with two or more longitudinally-projecting radially-disposed tenons a' and preferably with a keyway a^2 , adapted to receive a shaft-engaging key C, which is also engaged by a keyway e , formed in said section E, and which is preferably open at the end. I further construct a coöperating collar B, adapted to receive the end of a section e' of a power-shaft, which collar B is provided with two or more longitudinally-projecting radially-disposed dovetail tenons b' , adapted to project into recesses a^3 , formed by and between the tenons a' , the arc of each of tenons b' being shorter than the space a^3 , into which it projects, whereby it does not fill the same. The tenons of opposite collars, which preferably have their edges beveled to form dovetailed joints, may therefore be readily introduced into the recesses between the tenons of the respectively opposite collars, and a slight partial rotation in opposite directions of the respective sections of the shaft will cause the opposite tenons to interlock upon one of their respective edges, leaving a space between their other adjoining edges. These spaces are filled and the opposing tenons further secured in interlocked position by the insertion of radially-disposed key-wedges d , operating as separated transverse extensions of the adjoining tenons, each of which wedges is preferably provided at its outer end with a lip, as at d' , preferably beveled downwardly and inwardly on its lower face. The tenons b' are also preferably transversely beveled at one of their upper corners, as at b^3 , to admit within the periphery of said collar the heads of said wedges d , the lips d' whereof resting upon said beveled corner. The incline formed by said beveled corner b^3 is adapted also to permit the introduction of a foreign disengaging wedge or cutting-chisel under said lip d' , whereby said wedge may, if desired, be pried out or the head thereof cut off and the body otherwise by any suitable means or method removed. Said collar B is also preferably provided with a keyway b^4 , adapted to receive a shaft-engaging key c' , which is also engaged by a keyway e^4 , formed in said section e' and preferably open at the end; but said collars

may be secured to the respective sections of shaft by any suitable means or method within the scope of my said invention.

In operation I preferably first secure the respective collars, preferably by said keys, to their respective sections of the shaft and then bring them together, end on, into engagement with each other, the ends of the shaft abutting against each other, the keyways of the respective sections registering with each other, and the dovetail tenons of one collar projecting into the dovetail recesses of the opposing collar. The respective shafts are then given a partial rotation in respectively opposite directions to effect the interlocking of the tenons of one collar with the tenons of the opposite collar, which are then further locked in position by driving the key-wedges d from the periphery into the recesses resulting from the disparity between the width of said tenons and of said recesses, such key-wedges crowding the opposing tenons into further engagement and themselves operating as lateral extensions of said tenons to fill said recesses. Said wedges are designed to be retained by friction or compression. If desired to disengage them, a foreign disengaging wedge may be inserted under said lip d' to pry said wedge out, or the head of said wedge may be cut off and the remainder bored out or driven into the shaft-keyway and pushed out or removed by any other suitable means or method.

It will be seen that since the opposing edges of the tenons carried by the collars are beveled the shank of each key-wedge d is correspondingly beveled, so as to fit perfectly between the edged faces of said tenons. The key-wedges thus assist in completing the dovetailed connection between the collars and the coupling and make it impossible to pull the collars apart when the key-wedges are in place.

Having thus described my invention, what I claim as new, and desire to secure by Letters Patent, is—

1. In a shaft-coupling the combination of coöperating collars respectively secured to the opposing ends of opposite sections of a shaft, said collars each being provided with longitudinally-projecting dovetail tenons having arcs of less length than the respectively intervening spaces, the tenons on one collar being adapted to project into the recessed spaces formed by and between the tenons of the opposite collar and to engage the tenons of said opposite collar, a sufficient space being left between the edges of said tenons for the introduction of securing means, and securing means within said space, substantially as described.

2. In a shaft-coupling, the combination of coöperating collars respectively secured to the opposing ends of opposite sections of a shaft, said collars being provided with longitudinally-projecting radially-disposed dovetail tenons, having arcs of less length than the respectively intervening recessed spaces, the

tenons of one collar being adapted to project into recessed spaces formed by and between the tenons of the opposite collar and to engage the tenons thereof in interlocked position, means being interposed between one set of contiguous edges of said tenons for securing the same together, substantially as described.

3. A shaft-coupling comprising coöperating collars adapted to receive a shaft, each collar being provided with longitudinally-projecting radially-disposed dovetailed tenons of a less width than the spaces between the said tenons on each collar, the tenons of one collar being adapted to project into the recessed spaces formed between the tenons of the opposite collar, but not entirely filling the same, and means for filling the remainder of said spaces not occupied by said tenons for securing the said tenons of the opposing collars in interlocked position, substantially as described.

4. A shaft-coupling comprising coöperating collars adapted to receive a shaft, each collar being provided with longitudinally-projecting radially-disposed dovetail tenons having arcs of less length than the spaces intervening between the respective tenons of the opposite collar, the tenons of one collar being adapted to project into recessed spaces formed between the tenons of the opposite collar and to engage said tenons of said opposite collar in interlocked position; wedges between the edges of said tenons for securing the tenons of said opposite collars in interlocked position, substantially as described.

5. A shaft-coupling comprising coöperating collars adapted to receive a shaft, each collar being provided with longitudinally-projecting radially-disposed dovetail tenons having arcs of less length than the spaces intervening between the respective tenons of the opposite collar, the tenons of one collar being adapted to project into recessed spaces formed between the tenons of the opposite collar and to engage said tenons of said opposite collar in interlocked position; radially-disposed wedges adapted to fill the remaining space between adjoining interlocked tenons and to secure the same in interlocked position, substantially as described.

6. A shaft-coupling comprising coöperating collars adapted to receive a shaft, each collar being provided with longitudinally-projecting radially-disposed dovetail tenons of less width, respectively than the spaces intervening between the respective tenons of the opposite collar, the tenons of one collar being beveled laterally at one upper corner, the tenons of one collar being adapted to engage and interlock with the tenons of the opposite collar; and key-wedges for securing said tenons in interlocked position each formed with a disengaging lip at its upper end, substantially as described.

7. A shaft-coupling comprising coöperating collars secured to the ends of the shaft-sec-

tions which are to be coupled, the said collars having upon their meeting faces tenons formed with dovetailed edged faces, key-wedges having shanks formed with beveled faces corresponding with the beveled faces of the said tenons, the said wedges fitting between the edges of the tenons of the coöperating collars for completing a dovetail joint

between said collars, substantially as described.

In testimony whereof I hereunto affix my signature in presence of two witnesses.

OLE RUDD.
